(57) **CLAIM**

The ornamental design for a foldable handheld fan, as shown and described.

DESCRIPTION

FIG. 1 is a front elevational view of a foldable handheld fan, showing my new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a rear, top perspective view thereof;

FIG. 8 is a rear, bottom perspective view thereof;

FIG. 9 is a front elevational view of the foldable handheld fan of FIG. 1 in a fully extended configuration;

FIG. 10 is a rear elevational view thereof;

FIG. 11 is a left-side elevational view thereof;

FIG. 12 is a right-side elevational view thereof;

FIG. 13 is a top plan view thereof;

FIG. 14 is a bottom plan view thereof;

FIG. 15 is a front, top perspective view thereof; and,

FIG. 16 is a front, bottom perspective view thereof.

(Continued)

The broken lines in the figures represent portions of the foldable handheld fan that form no part of the claimed design.
